LAUNDRY SOUR

Adolph V. Klancnik and Frank J. Klancnik,
Chicago, Ill.No Drawing. Application October 10, 1942,
Serial No. 461,636

5 Claims. (Cl. 252—145)

This invention relates to a sour and more particularly to a laundry sour used to neutralize excessive amounts of residual alkali in washing and rinsing waters.

Laundry sours as heretofore provided served to neutralize the residue alkali and soap in the washing and rinsing waters usually to an acid pH of 4.0 to 6.5. Their tendency was to decompose the soap and to go toward neutral and sometimes to the alkaline side upon drying, thus causing discoloration due to the heat upon ironing. Consequently, the effects of the tinting solutions, such as the well known bluings, were nullified and the finished fabrics acquired an undesirable brownish color.

An object of the present invention is to provide a highly improved laundry sour adapted to change the washing waters or solutions from the alkaline side to a slightly acid condition and maintain the same during rinsing and tinting operations and upon drying and ironing. It is known that the tinting solutions better perform their function in an acid bath and that the effects of tinting will be more satisfactory and a better appearance produced, particularly in the case of white linens, if the clothes will remain slightly acid after they are ironed. The present invention is accordingly directed to a laundry sour that will assure a slightly acid condition of the washing and rinsing waters so that the tinting will take place in an acid bath, and further, that will assure that the clothes will remain slightly acid after they are ironed.

Although an excessive acid pH in the washing and rinsing waters is undesirable because it is destructive and tends to break down the fabric, it was necessary heretofore to add an excessive amount of sour if a slight acid condition were to be maintained in the finished goods, due to the tendency of these prior art sours to go to neutral and even to the alkaline side upon drying. The amount of sour that had to be added to secure a slight acid condition of the finished goods depended of course upon the bicarbonate content of the water, and where this content was high, greater quantities of sour had to be used and sometimes to an extent that considerable damage would be caused to the finished goods. An excess acid condition of the washing and rinsing waters also caused an undesirable heaviness or stiffness in the finished goods after ironing, due to an apparent filling action of the interstices and possibly of the pores of the fabric. The laundry sour disclosed herein produces a slight acid condition in the laundering waters, which

is so controlled that it will be maintained throughout the laundering and tinting operations and will be present in the finished goods. The acid pH that is produced will not be excessive and will not be harmful to the goods. One of the features of the invention is directed to providing a sour that will drop the acid pH value slightly under 7.0, say, in the neighborhood of from 6.9 to 6.5, which is a very desirable range for tinting and producing the appearance necessary for the finished goods. This acid condition is maintained throughout the laundering and tinting operations and will not be lost by the heat upon ironing. The excessive acid condition heretofore encountered, and that at times showed a pH as low as 4.0, is avoided and a condition assured that remains constant and produces efficient results.

More specifically the invention is preferably directed to a laundry sour comprising a mixture employing ammonium chloride as its base and a magnesium carbonate as a buffer for the base to prevent the ammonia from separating from the chloride. In case the ammonium chloride tends to cake or lump, a small amount of starch may be employed to produce a dusting effect upon the ammonium chloride. We have found that if a small amount of acid, such as oxalic acid or a fluoride, is added to this mixture, the acid pH can be definitely controlled so that a pH slightly below 7.0 can be obtained and be held not only in the washing and rinsing waters but in the finished goods. With this slightly acid condition, the bluing dyes added to the bath will effect an efficient tinting action that produces a desirable appearance of the finished goods. We have found that discoloration is effectively eliminated and the fabric will be in a natural uniform state without the aforesaid stiffness or heaviness heretofore experienced when an excessive acid pH had to be used in the washing and rinsing waters to secure a slight acid pH in the finished goods.

Specific examples of the laundry sour will be found in the use of a mixture consisting of 97.5% of ammonium chloride and from $\frac{1}{2}$ to 2% of magnesium carbonate, which, when mixed and added to the washing and rinsing solutions, will produce an alkaline pH from 7.2 to 7.4. In the event it is desirable to prevent caking of the ammonium chloride, these proportions may be changed to permit the use of 2 to 10% of starch or other equivalent material to secure the desired dusting effect upon the ammonium chloride. To secure the aforesaid controlled acid condition that will remain reasonably constant in the

washing waters and appear in the finished goods, a fluoride or oxalic acid may be added. The amount of acid to be added may vary, but we have found that anywhere between 2 to 10% will be satisfactory. Of the different fluorides that may be used, sodium silico fluoride, ammonium fluoride, ammonium silico fluoride ammonium acid fluoride and sodium acid fluoride are mentioned. It is intended to use in the mixture any desirable acid in the proportions that may be necessary, and consequently, we do not wish to be limited in this respect.

While it may be desirable to add the percentage of ammonium chloride mentioned because good results have been obtained, it will be apparent that the scope of the invention extends to the use of varying amounts and that this percentage may be changed within a considerable range. The same is true with the buffer and the duster mentioned and also with respect to the type of buffer and duster used. We have found that these amounts depend somewhat upon the conditions at the time.

The results produced showed efficient neutralizing of excessive residue alkali in the washing and rinsing waters and efficient tinting in the tinting baths. Although a slight acid condition is produced, it will remain and cause the clothes to be also slightly acid after ironed in order to have the most favorable appearance when finished. A further advantage to be obtained resides in the fact that the materials mentioned are relatively inexpensive and may be easily obtained.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which

items are intended to be defined and secured to us by the following claims.

We claim:

1. A laundry sour comprising a dry mixture containing about 97.5% of ammonium chloride and from 0.5% to 2.5% of magnesium carbonate.
2. A laundry sour comprising a dry mixture containing about 97.5 parts of ammonium chloride, 0.5 to 2.5 parts of magnesium carbonate, and from about 2 to 10 parts of a water-soluble acid-reacting substance selected from the group consisting of the acid-reacting fluorides and oxalic acid.
3. A laundry sour composition comprising a dry mixture containing a major portion of ammonium chloride, a minor portion of magnesium carbonate in an amount sufficient to prevent the development of excess acidity upon dispersion of the composition in water, and an amount of a water-soluble acid-reacting compound selected from the group consisting of the acid-reacting fluorides and oxalic acid sufficient to impart to an aqueous dispersion of the composition a pH of about from 6.9 to 6.5.
4. A laundry sour comprising a dry mixture containing a major portion of ammonium chloride and a minor portion of magnesium carbonate, the latter in an amount sufficient to prevent the development of excess acidity upon a dispersion of the composition in water.
5. A laundry sour in dry form comprising a major portion of ammonium chloride, a minor portion of magnesium carbonate in an amount sufficient to prevent development of excess acidity upon the dispersion of the composition in water, and sufficient starch adhering to the ammonium chloride to prevent the adhesion of the ammonium chloride particles to each other in the dry composition.
